UNITED STATES PATENT OFFICE.

CHESTER A. SAYBOLT, OF PHILADELPHIA, PENNSYLVANIA, ASSIGNOR TO LOCKWOOD FOLDING BOX COMPANY, OF PHILADELPHIA, PENNSYLVANIA, A CORPORATION OF PENNSYLVANIA.

EASEL DISPLAY-CARTON.

1,296,223.

Specification of Letters Patent.

Patented Mar. 4, 1919.

Application filed May 13, 1918. Serial No. 234,059.

To all whom it may concern:

Be it known that I, CHESTER A. SAYBOLT, a citizen of the United States of America, residing at Philadelphia, in the county of Philadelphia and State of Pennsylvania, have invented certain new and useful Improvements in Easel Display-Cartons, of which the following is a specification.

This invention relates to certain new and useful improvements in an easel display carton, and it has for its primary object to provide a combined carton and easel support therefor foldable from a unitary blank in a simple and expeditious manner.

It is a further aim to provide a carton which so folds that when the blank is glazed or colored on one side only, the glazed finish will be presented over the entire inside and outside surface of the box or receptacle, leaving no unglazed part to view.

Further, the invention resides in the salient features of construction hereinafter described in detail and claimed in a succinct manner, reference being had to the accompanying drawings, wherein:

Figure 1 is a side elevation of the completed carton having its easel support operative.

Fig. 2 is a rear elevation thereof.

Fig. 3 is a longitudinal, vertical section therethrough.

Fig. 4 is a longitudinal, horizontal section through the carton on line 4—4 of Fig. 3.

Fig. 5 is a transverse section on line 5—5 of Fig. 3.

Fig. 6 is a plan view of the blank from which the carton is folded.

Fig. 7 is a fragmentary plan view of a modified form of the invention.

Fig. 8 is a perspective view of a carton embodying the modification, and

Fig. 9 is a transverse section on line 9—9 of Fig. 8 further illustrating the invention.

Referring more in detail to the drawings, the blank from which the preferred embodiment is folded is substantially cruciform, comprising an exterior bottom section 1 having exterior side sections 2 joined thereto by scored lines of fold 3, which side sections are in turn connected to interior side sections 4 by fold lines 5.

To the opposite ends of the exterior sides 2 are foldably joined along lines 6 end wall

sections 7 and 8, which fold in overlapping relation as depicted in Fig. 4.

One end wall section 8 has a tongue extension 9 that is inserted in slit 10 formed in the hinge mounting of the companion section 8 for holding both sections operative. The opposing end wall sections 7 are retained operative by an exterior end section 11 which is foldably joined to one end of bottom section 1, as at 12 and from this exterior end section 11 extends a strip like length of slightly narrower width, as indicated at 13, said strip being divided transversely by lines of fold 14 into an interior end section 15, an interior bottom section 16, a second interior end section 17 and a display tab or sign card section 18.

The easel support for the carton comprises a leg section 19, joined to the opposite end of the bottom section 1 by fold line 20, a brace section 21, hingedly connected to section 19 at 22, and a locking tongue 23 of reduced width and joined to the section 21 by fold line 24. The sections 19 and 21 when operative provide a V-shaped easel support or leg for elevating the adjacent end of the carton and thereby dispose the latter at an inclination. To maintain the easel support sections folded, the tongue 23 is inserted through a dovetail-shaped slit 25 in the bottom section 1, as depicted in Fig. 3.

In folding the carton from the blank shown in Fig. 6, the interior side sections 4 are initially folded over onto the exterior side sections 2 and the latter are then turned upwardly at right angles to the exterior bottom 1 on lines 3. End wall sections 8 are then folded to overlap each other with the one bearing tongue 9 disposed outwardly so that said tongue may be inserted inwardly through slit 10 to hold the end wall sections and the side walls operative.

The end wall sections 7 are next folded to overlap each other and then exterior end section 11 is turned up against the outer one and interior end section 15 is folded over and down between the side walls into contact with the inner wall section 7. This disposes the interior bottom member 16 down onto bottom member 1 and between the free edges of side section 4 to hold them spaced apart. The interior end section 17 lies in contact with the inner end wall section 8.

and leaves the sign card or tab 18 extending well above the box. The easel support may now be folded under the carton and retained operative by inserting tongue 23 through 5 slit 25.

The carton is now in its display form or the form in which its contents may readily be observed. In shipping the carton, the tongue 23 is removed from slit 25 and section 19 folded up against the outer end wall section 8. Section 21 is then folded together with tab 18 down into the box, after which the box may then be slipped into a tubular casing of rectangular section as indicated 10 at 26 in Fig. 5.

The modified form obviates the necessity of an enveloping casing 26 by providing an integral cover consisting of a top section 27, triangular side sections 28 and an end section 29. The side sections gradually increase in depth and at their outer edges carry flaps 30 formed with slots 31 and foldable over in front of end section 29, the free end 32 of which is turned inwardly and 20 upwardly against the flaps 30 with its corners engaged in the slots 31 to lock the sides and ends operatively. The fold lines 33 extend as continuations of the side edges of the easel support section 21, while transverse fold lines 34 divide off the flaps and 25 end sections.

When folded, the cover extends well down over the carton at one end and efficiently serves to close the box. For use as a display carton the cover is removed on the 30 weakened line 35, which defines the section 21 and tab 23, thereby leaving the carton equal to that shown in Figs. 1 to 6, inclusive.

A box constructed in accordance with this 40 invention presents a like finish interiorly as well as exteriorly, even though one surface only of the stock be glazed or prepared. No gluing or other extra fastening means is employed and yet a strong, durable and 45 rigid structure is obtained. The inclination at which the box is displayed may be varied by lengthening or shortening the easel support. The carton and easel support are unitary, being folded from a single blank of 50 stock.

What I claim is:

1. A carton formed from a single blank of cross-form and folded to provide interior and exterior, wall and bottom sections, one 55 interior wall section extended to provide a sign card.

2. A carton foldable from a cruciform blank divided by scored lines to provide interior and exterior side sections, end wall 60 sections, easel support sections, and a depending strip-like member foldable over the adjacent end wall sections down into the receptacle between the interior side sections and up against the remote end wall sections 65 and then extended to provide a sign card.

3. A display carton foldable from a single blank scored to provide an exterior bottom member, exterior side sections joined thereto, interior side sections joined to the exterior side sections and foldable thereonto, end 70 wall sections joined to the ends of the exterior side sections and foldable over each other to provide double end walls, an exterior end section joined to one end of the bottom member for folding up against the adjacent end wall, an interior end section joined to the exterior end section for folding over and down into contact with the inner side of said end wall, an interior bottom member joined to the interior end section for overlying the exterior bottom member and for holding the free edges of the interior side sections spaced apart, and a second interior end section joined to the opposite end of the interior bottom member 80 for contact with the adjacent end wall of the carton.

4. A display carton foldable from a single blank scored to provide an exterior bottom member, exterior side sections joined thereto, interior side sections joined to the exterior side sections and foldable thereonto, end wall sections joined to the ends of the exterior side sections and foldable over each other to provide end walls, an exterior end section joined to one end of the bottom member for folding up against the adjacent end wall, an interior end section joined to the exterior end section for folding over and down into contact with the inner side of said end wall, an interior bottom member joined to the interior end section for overlying the exterior bottom member and for holding the free edges of the interior side sections spaced apart, a second interior end section joined to the opposite end of the interior bottom member for contact with the adjacent end wall of the carton and a sign card joined to the free upper edge of the second interior end section.

5. A display carton foldable from a single blank scored to provide an exterior bottom member, exterior side sections joined thereto, interior side sections joined to the exterior side sections and foldable thereonto, end wall sections joined to the ends of the exterior side sections and foldable over each other to provide end walls, an exterior end section joined to one end of the bottom member for folding up against the adjacent end wall, an interior end section joined to the exterior end section for folding over and down into contact with the inner side of said end wall, an interior bottom member joined to the interior end section for overlying the exterior bottom member and for holding the free edges of the interior side sections spaced apart, a second interior end section joined to the opposite end of the interior bottom member for contact with the adjacent end 115 wall.

- wall of the carton, a sign card joined to the free upper edge of the second interior end section, a leg section joined to the opposite end of the exterior bottom member, foldable downwardly therebeneath, a brace section joined to the leg section and a securing tab joined to the brace section for insertion through a slit provided in the exterior bottom member.
- 10 6. A display carton foldable from a single blank scored to provide an exterior bottom member, exterior side sections joined thereto, interior side sections joined to the exterior side sections and foldable thereonto, end wall sections joined to the ends of the exterior side sections and foldable over each other to provide end walls, an exterior end section joined to one end of the bottom member for folding up against the adjacent end wall, an interior end section joined to the exterior end section for folding over and down into contact with the inner side of said end wall, an interior bottom member joined to the interior end section for overlying the exterior bottom member and for holding the free edges of the interior side sections spaced apart, a second interior end section joined to the opposite end of the interior bottom member for contact with the adjacent end wall of the carton, a sign card joined to the free upper edge of the second interior end section, a leg section joined to the opposite end of the exterior bottom member, foldable downwardly therebeneath, a brace section joined to the leg section, and a cover also joined to the brace section and removable therefrom whereby the brace section may be operatively disposed relative to the body of the carton and subsequent to the opening of the latter to serve as an easel support therefor.
7. A display carton foldable from a single blank scored to provide an exterior bottom member, exterior side sections joined thereto, interior side sections joined to the exterior side sections and foldable thereonto, end wall sections joined to the ends of the exterior side sections and foldable over each other to provide end walls, an exterior end section joined to one end of the bottom member for folding up against the adjacent end wall, an interior end section joined to the exterior end section for fold-
- ing over and down into contact with the inner side of said end wall, an interior bottom member joined to the interior end section for overlying the exterior bottom member and for holding the free edges of the interior side sections spaced apart, a second interior end section joined to the opposite end of the interior bottom member for contact with the adjacent end wall of the carton, a leg section joined to the opposite end of the exterior bottom member foldable downwardly therebeneath, a brace section joined to the leg section, and a securing tab joined to the brace section for insertion through a slit provided in the exterior bottom member.
- 15 8. A display carton foldable from a single blank scored to provide an exterior bottom member, exterior side sections joined thereto, interior side sections joined to the exterior side sections and foldable thereonto, end wall sections joined to the ends of the exterior side sections and foldable over each other to provide end walls, an exterior end section joined to one end of the bottom member for folding up against the adjacent end wall, an interior end section joined to the exterior end section for folding over and down into contact with the inner side of said end wall, an interior bottom member joined to the interior end section for overlying the exterior bottom member and for holding the free edges of the interior side sections spaced apart, a leg section joined to the opposite end of the exterior bottom member foldable downwardly therebeneath, a brace section joined to the leg section, a securing tab joined to the brace section for insertion through a slit provided in the exterior bottom member.
- 20 9. A carton formed from a single blank to provide an open top body, an easel support therefor, and a cover member, the easel support and the cover member cooperating to close the top of the carton body, and the cover member being readily detachable from the easel support to allow the latter to function.
